UNITED STATES PATENT OFFICE

2,497,128

IRONING APPARATUS

John H. Leef, Minneapolis, Minn.

Application November 15, 1947, Serial No. 786,218

1 Claim. (Cl. 38—5)

1

My invention relates to garment ironing or pressing machines and more particularly to machines incorporating a plurality or gang of individual pressing or ironing devices.

The primary object of my invention is to provide a novel arrangement of a plurality of individual pressing devices to facilitate operation of all thereof by a single operator.

A still further object of my invention is the provision of novel means for supplying the individual pressing units with fluid heating medium and also with fluid pressure for automatic operation of the units.

A still further object of my invention is the provision of novel control means for successively operating the individual machines.

The above and still further objects and advantages of my invention will become apparent from the following detailed specification, appended claim, and attached drawings.

Referring to the drawings wherein like characters indicate like parts throughout the several views:

Fig. 1 is a plan of my improved ironing machine, some parts being broken away and some parts shown in section;

Fig. 2 is an enlarged section taken substantially on the line 2—2 of Fig. 1;

Fig. 3 is a still further enlarged fragmentary section taken on the line 3—3 of Fig. 2; and

Fig. 4 is an enlarged axial section taken through an improved central manifold utilized in connection with my invention.

Referring with greater particularity to the drawings, the numeral 1 indicates a circular track upon which is mounted for rotation a turntable indicated in its entirety by the numeral 2, and comprising an annular mounting plate 3 reinforced at its inner edge by a depending flange 4 and at its outer periphery by a depending L-shaped flange 5. The turntable 2 is supported on the rail 1 by means of rail-engaging wheels 6 journaled in bearing flanges 7, welded or otherwise secured to the undersurface of the plate 3. The turntable 2 is further reinforced by radial arms 8 connected at their outer ends thereto and at their inner ends to a central ring 9.

The turntable may be rotated by any power-driven mechanism, but preferably, and as shown, is power-driven from a motor 10 and a driving link chain 11. The driving link chain 11 extends around the turntable 2 and frictionally engages the same within a channel 12 formed by the outer periphery of the annular plate 3 and the L-shaped flange 5. The link chain 11 runs over

and is driven by a sprocket 13 mounted on a driving shaft 14 journaled in a gear housing 15. The driving shaft is coupled to the shaft of the motor 10 by means of gears, not shown, but contained within the gear housing 15. An idler pulley 16 is journaled in one end of a bell crank 17. The intermediate portion 18 is pivoted to a quadrant 19, which is rigidly secured to the gear housing 15. A spring pressed pin and slot connection 20 on the bell crank 17 and quadrant 19 is utilized to lock the bell crank in a desired position. Movement of the bell crank 17 in one direction will move the idler pulley 16 into engagement with the chain 11 whereby to increase the frictional engagement therebetween and the base of the channel 12 for driving the turntable. Obviously, the movement of the bell crank 17 in the opposite direction will move the idler pulley 16 away from engagement with the chain 11 and allow the chain to slip in the channel 12.

Mounted fast on the top plate 3 is a plurality of circumferentially-spaced pressing or ironing devices 21 each having a relatively stationary pressing element 22 and a relatively movable element 23. As shown in Fig. 2, the fixed elements 22 are mounted on pedestal-like bases 24 and the relatively movable elements 23 are each pivoted to their respective bases 24, as indicated at 25. Each movable element 23 is connected within its base 24 to the outer end 26 of a piston-equipped plunger rod 27 slidably mounted in a fluid pressure cylinder 28, which is hinged at one end, as indicated at 29, to the pedestal 24. A coil compression spring 30 within each cylinder 28 biases the movable element 23 in the direction of its cooperating relatively stationary element 22.

Each movable element 23 is adapted to be moved away from its cooperating relatively fixed element 22 against bias of the spring 30 by fluid under pressure introduced into each cylinder 28 through a conduit 31. Each conduit 31 is connected to a 3-way valve 32 secured to the top plate 3 within each pedestal 24 by means of a bracket 33. The valve 32 is of a conventional type and is operated by means of a crank arm 34. Crank arm 34, in turn, is connected at its free end to a link 35 which, in turn, is pivotally secured, as indicated at 36, to the free end of a lever arm 37. The lever arm 37 is intermediately pivotally secured to a bracket 38 fast on the under side of the top plate 3, as indicated at 39; and to its bifurcated free end 40 is journaled a cam follower wheel 41. It will be understood that there is a separate cam fol-

lower equipped lever 37 and link 35 for actuating each valve 32. The cam followers 41, as indicated by dotted lines in Fig. 3, are adapted to bear against the floor or ground adjacent the circular track 1, and to engage a segmental cam element 42, which is concentric to the circular track 1 adjacent an operator's station, indicated by broken lines in Fig. 1 and by the letter S. Crank arm 34, in turn, is connected at its free end to a link 35 which, in turn, is pivotally secured, as indicated at 36, to the free end of a lever arm 37. The lever arm 37 is intermediately pivotally secured to a bracket 38 fast on the under side of the top plate 3, as indicated at 39; and to its bifurcated free end 40, is journalled a cam follower wheel 41. It will be understood that there is a separate cam follower equipped lever 37 and link 35 for actuating each valve 32. The cam followers 41, as indicated by dotted lines in Fig. 3, are adapted to bear against the floor or ground adjacent the circular track 1, and to engage a segmental cam element 42, which is concentric to the circular track 1, adjacent an operator's station, indicated by broken lines in Fig. 1 and by the letter S.

Engagement of the wheel 41 by the cam element 42 positions the three-way valve 32 to allow fluid under pressure to be introduced into the cylinders 28, whereby to move the movable element 23 away from the relatively fixed element 22. Disengagement of the wheel 41 from the cam element 42, as indicated by dotted lines in Fig. 3, will position the valve 32 so as to block fluid under pressure from the cylinder 28 and to allow fluid within the cylinder 28 to escape to atmosphere through a port 32' in the valve 32. Exposure of the fluid interior of the cylinder 28 to atmosphere will allow bias of the spring 30 within the cylinder 28 to move the movable element 23 toward the relatively fixed element 22. Fluid under pressure is conducted to said valve 32 by fluid pressure conduit means hereinafter to be described.

Each of the relatively fixed ironing elements 22 is heated by a fluid heating medium such as live steam conducted to the interior thereof from a source not shown through a downwardly-extending pipe 43 (coaxial to the track 1 and the turntable 2), an inlet manifold 44, and fluid heating medium transfer means in the nature of radially-projecting pipes 45 leading one each from the inlet manifold 44 to one each of the elements 22. Condensate is removed from the elements 22 through radially inwardly projecting pipes 46 which terminate in an outlet manifold 47 underlying and rigidly secured in spaced relationship to the inlet manifold 44 by means of circumferentially spaced legs 48. From thence, condensate is drained off through a fixed drain pipe 49.

Rotation of the turntable 2 causes common rotation of the manifolds 44 and 47, due to the connections 45 and 46 therewith. The rotary manifolds 44 and 47 are coupled to their respective fixed pipes 43 and 49 by means of fluid tight swivel joints 50 and 51. The swivel joints 50 and 51 are of conventional type and, as shown, comprise a male element 52 swivelled within a female element 53 and held therein by an annular retaining nut 54. It will be seen, particularly by reference to Figs. 2 and 4, that the female element of the swivel joint 51 is connected to a pipe T 55. A nipple 56 and an elbow 57 connect the pipe T to the drain pipe 49. It will be further seen, by reference to Figs. 1, 2, and 4,

that the pipes 45 and 46 are circumferentially spaced about the peripheral portions of the manifolds 44 and 47 respectively.

Fluid under pressure is conducted through the several three-way valves 32 from a common source of pressure not shown through a fixed conduit 58 which terminates in the female element 59 of a swivel joint 60 directly underlying the T joint 55. A rotary conduit 61 is rigidly secured at its lower end to the male element 62 of the swivel joint 60 and extends axially upwardly through the T joint 55, the swivel joint 51, and the outlet manifold 47, to the upper wall of which it is rigidly secured by means of welding or the like, as indicated at 63. Leakage is prevented between the lower end of the pipe T 55 and the rotary conduit 61 by a packing gland 64. The extreme upper end of the rotary conduit 61 projects through the top wall of the outlet manifold 47 and is rigidly connected to a radially extending conduit 65 by means of an elbow or the like 66. The conduit 65 is connected to the several three-way valves 32 by connections including an annular conduit 67 and branch lines 68.

The operation of my novel structure is generally as follows: A single operator may position himself at the operator's station S. As each ironer approaches the operator's station, the cam follower wheel 41 associated therewith, is engaged by the cam element 42, with the result that the three-way valve is positioned to allow fluid under pressure to enter the cylinder 28 and move the movable member 23 away from the relatively fixed member 22. The pressing machine is then in a position to allow the operator to remove pressed clothing therefrom and/or to put unpressed clothing thereon. As each cam follower wheel 41 leaves the cam element 42, it assumes the dotted line position indicated in Fig. 3, allowing fluid to escape from the interior of the cylinder 28 through its associated valve 32 to atmosphere; and bias of the spring 30 moves the movable element 23 into contact with the garment which has been placed on the relatively fixed element 22. The speed of rotation of the turntable is such that the portion of the garment between the elements 22 and 23 will be completely ironed as the ironer again approaches the operator's station. As the follower wheel 41 again engages the cam element 42, the movable element 23 is moved away from the relatively fixed element 22, thus leaving the ironer in a condition for an operator to move the garment thereupon or to remove it from the ironer altogether and apply another garment thereto.

My invention has been thoroughly tested and found to be completely adequate for accomplishment of the objectives set forth; and, while I have shown a commercial form of the invention, it will be understood that the same is capable of modification without departure from the spirit and scope of the invention as defined in the claim.

What I claim is:

65 A coupler for connecting each of a plurality of pressing machines movably mounted on a circular track to independent relatively fixed sources of supply of fluid under pressure and a drain, said pressing machines each comprising a relatively fixed and relatively movable pressing element, one of which elements is adapted to be heated by a fluid heating medium, and fluid pressure operated means for moving the movable pressing element in one direction with respect to its cooperating relatively fixed element, said

coupler being coaxial with said track and comprising axially aligned rotatable inlet and outlet manifolds rigidly secured together in closely spaced relationship, a fixed inlet pipe axially aligned with and overlying said inlet manifold, a fixed drain pipe underlying said outlet manifold and axially aligned therewith, fluid tight swivel joints connecting each of said manifolds with its adjacent fixed pipe, said manifolds each having a plurality of ports adapted to be in communication one each with a pressing element on each of said machines, a rotary fluid pressure conduit extending axially through said outlet manifold and drain pipe, a second fixed inlet pipe and a fluid tight swivel joint connecting the lower end of said rotary conduit to said second fixed inlet pipe, said

rotary conduit terminating in the space between said manifolds for connection to said fluid operated means.
